UNITED STATES PATENT OFFICE.

WILLIAM MASON, OF HARTFORD, CONNECTICUT, ASSIGNOR TO THE COLTS PATENT FIRE-ARMS MANUFACTURING COMPANY, OF SAME PLACE.

TRIGGER FOR DOUBLE-BARRELED FIRE-ARMS.

SPECIFICATION forming part of Letters Patent No. 247,379, dated September 20, 1881.

Application filed June 13, 1881. (No model.)

To all whom it may concern:

Be it known that I, WM. MASON, of Hartford, in the county of Hartford and State of Connecticut, have invented a new Improvement 5 in Double-Barrel Fire-Arms; and I do hereby declare the following, when taken in connection with the accompanying drawings and the letters of reference marked thereon, to be a full, clear, and exact description of the same, 10 and which said drawings constitute part of this specification, and represent, in—

Figure 1, a side view; Fig. 2, a top view; Fig. 3, a rear end view.

This invention relates to an improvement in 15 that class of fire-arms commonly called "double-barrel," or such as employ two triggers, each for the respective hammers of the arm.

Many accidents in the use of this class of 20 arms have occurred because of the person using the arm pulling both triggers, when he intended to pull but one.

The object of this invention is to overcome 25 this difficulty; and it consists in combining with the two triggers of a fire-arm a locking mechanism, arranged to be operated by the pulling of either trigger, and be thereby applied to prevent the action of the other trigger, as more fully hereinafter described.

A is the guard-plate, to which the two triggers B C are hung, in the usual manner. Upon 30 the upper or inside of the guard-plate, and in rear of the triggers, a two-armed lever, a b, is arranged upon a transverse pivot, d, one arm extending forward, the other rearward. The forward arm, a, bears upon the rear end of the back of the trigger B. The back of the trigger C is extended to the rear, so as to come beneath the arm b, it being cut away from its rear end forward, so as to escape the arm a,

as seen in Fig. 1. Now, if the trigger C be 40 pulled, it raises the arm b, and correspondingly depresses the arm a to bear upon and press down the trigger B, or vice versa; hence but one trigger can be brought to bear at the same time, and that may be either the one or the 45 other.

I have described the invention as applied to the triggers of an arm; but it will be evident to those skilled in the art that in those arms in which sears are used this device may be applied to the sears instead of to the triggers; hence by the term "triggers" I wish to be understood as embracing not only the arms which employ independent sears, but arms in which the sear is a part of the trigger. 55

While I believe the construction and arrangement I have described to be the best for practical use, other mechanism may be introduced, of substantially the same character, to produce the same result, it only being essential 60 that the pulling of one trigger or sear shall automatically apply a stop to the opposite trigger or sear at some point between the finger-piece of the trigger and the hammer, so as to prevent the pulling of the said opposite 65 trigger or sear.

I claim—

In combination with the two triggers of a fire-arm, a locking mechanism, substantially such as described, arranged to be operated by 70 the pulling of either trigger, and be thereby applied to prevent the action of the other trigger, substantially as described.

WILLIAM MASON.
